UNITED STATES PATENT OFFICE

168,105

MERCURY ACTUATED ADJUSTABLE DIAL
TYPE THERMOMETER

Curtis P. Mitchell, North College Hill, and Charles C. Bernitt, Newtown, Ohio, assignors to Palmer Thermometers, Inc., Norwood, Ohio, a corporation of Ohio

Application July 13, 1951, Serial No. 15,862

Term of patent 14 years

(CL. D52—7)

To all whom it may concern:

Be it known that we, Curtis P. Mitchell and Charles C. Bernitt, citizens of the United States, residing at North College Hill and Newtown, in the county of Hamilton and State of Ohio, respectively, have invented a new, original, and ornamental Design for a Mercury Actuated Adjustable Dial Type Thermometer, of which the following is a specification, reference being had to the accompanying drawings, forming part thereof:

Fig. 1 is a front elevational view of a mercury actuated adjustable dial type thermometer, showing our new design.

Fig. 2 is a side elevational view of the device of Fig. 1.

Fig. 3 is a rear elevational view of the device of Fig. 1.

Fig. 4 is a top plan view of the device of Fig. 1.

Fig. 5 is a side elevational view similar to Fig. 2, illustrating the adjustable features of the device.

The essential features of the design reside in the solid line portions.

We claim:

The ornamental design for a mercury actuated adjustable dial type thermometer, as shown and described.

CURTIS P. MITCHELL.
CHARLES C. BERNITT.
